REGINALD FERGUSON, OF MONTREAL, QUEBEC, CANADA, ASSIGNOR TO SIMMONS LIMITED, OF MONTREAL, QUEBEC, CANADA

BOTTOM CONSTRUCTION FOR BEDSPRINGS AND THE LIKE

Application filed November 2, 1927. Serial No. 230,664.

This invention relates broadly to improvements in bed springs and bed bottoms, and more particularly to springs of the upright spiral-helical type.

The main object of the invention is to provide greater resiliency near the ends of the spring where but little weight is carried than at the centre where the greater part of the weight is carried, thereby to eliminate centrally localized sagging in use.

In the manufacture of bed springs of the upright coil type, the aim heretofore has been to make the spring bottom upon which the upright coils rest such as to give uniformly rigid support to the coils. Departure from this aim has been in the direction of less rigidity at the centre of the spring due to yielding of the spring bottom when under load and has been avoided as far as possible owing to the disadvantage that it induces a central sag in the spring top. When sufficiently rigid bottom construction and sufficiently stiff coils are used to avoid excessive sagging in the centre where the greatest weight is carried, the ends of the spring where but little weight is carried are lacking in resiliency and the effect or sensation is much the same as if an excessive sag existed.

According to this invention, instead of stiffening the centre part of the spring, the resiliency of the ends is increased, so that the spring yields at the ends to approximately the same extent as it yields in the centre. In this way, back straining sagging is eliminated and the spring becomes more comfortable to sleep on, by reason of resiliency at the ends instead of rigidity. The result is obtained by use of flexible or resilient bottom supports for the upright coils toward the ends of the spring, while rigid bottom supports are used in the central part of the structure. If desired, the upright coils resting on the flexible supports may be more resilient than the coils resting on the rigid supports but, ordinarily, this is not necessary and from a manufacturing point of view is not desirable.

In the drawings which illustrate one em-

bodiment of the invention but to the details of which the invention is not confined;—

Fig. 1 is a plan view of a bed spring bottom formed according to the invention.

Fig. 2 is a fragmentary transverse sectional view of the spring bottom at the line 2—2 of Figure 1, on an enlarged scale.

Fig. 3 is a fragmentary longitudinal sectional view on the line 3—3 of Figure 1 and on the same scale as Figure 2.

Figs. 4 and 5 illustrate various forms of resilient coil supports.

Referring more particularly to the drawings, 11 designates the side rails of a bed spring bottom, which are of any suitable material and cross section, and 12 designates a series of rigid transverse members of any suitable material and cross section connected between the side rails at the ends and at the central parts thereof. Toward the ends of the bottom frame, resilient and preferably flexible transverse members 13 are connected between the side rails. While only one resilient member 13 has been shown toward each end of the spring bottom, it will be understood that the number may be increased as necessary or desirable.

The resilient members may take a variety of forms of which the most simple is illustrated in Figure 1, namely, a spring wire connected at its ends to the side rails and formed in its central part into a helical spring 14. While only one spring is shown in the length of the support, it will be understood that the number and arrangement of the springs may be varied as desired, for example, as shown in Figure 4, wherein springs are formed toward both ends of the support leaving the centre plain. In any wire support the spring or springs 14 may be formed integral with the wire or otherwise, as desired. A further form of resilient support is shown in Figure 5 and includes a bar 15 and springs 16 at the ends thereof to resiliently support the bar between the side rails. The springs 16 may be connected to the bar 15 and to the side rails in any way desired.

The upright spring units 17 of the bed spring rest upon the supports 12 and 13 and are tied thereto in any usual or suitable man-

ner, for example, by locking wires 18 extending longitudinally of the bottom frame.

When a person lies upon the spring, the rigidly supported upright spring units in the central part where the greatest load is located are compressed and the spring top (not shown) tends to sag in the centre. The resiliently supported upright spring units under the sleeper's head and feet are somewhat compressed and are in addition moved bodily downward as the supports yield, with the result that the spring top is pressed downward at the head and foot of the spring to approximately the same extent as the central part. The usual sensation of a sagged spring is not experienced, because the sag has been extended under the sleeper's whole body instead of being concentrated under the trunk. In this way, the much desired restful feeling of lying on a level surface is experienced, together with the comfort of lying on a freely resilient spring. It will thus be seen that, instead of opposing the central sagging with uncomfortably rigid structures, the central part of the spring is allowed to sag and the sagging is invited at or extended to the ends of the spring.

A great advantage of the present invention is that in its simple forms, it reduces the cost of bed springs and may therefore be applied equally to the cheapest and to the most expensive springs and to upright coil springs of all types, whereas efforts formerly made to stiffen springs against sagging added materially to the cost and were therefore not applicable to cheaper grades of springs.

While the invention relates primarily to bed springs of the upright coil type, it is applicable in principle to and extends to other types of bed bottoms, particularly side supported fabric bottoms.

Having thus described my invention, what I claim is:—

1. A bed spring comprising side rails, rigid members rigidly connected to the central parts of said side rails and extending transversely from rail to rail and flexible wires including helical springs connected to the rails toward the ends thereof and extending transversely from rail to rail and upright spring unit supported on said rigid and flexible members and means connecting the tops of said upright coil springs.

2. A bed spring comprising side rails, flat bars disposed edge up and rigidly connected to the central parts of said side rails, and wires connected to the side rails toward the ends thereof, said wires including helically formed spring portions and upright coil springs supported on said bars and wires and means connecting the tops of said upright coil springs.

3. In a bed spring, the combination of side rails, flat bars disposed edge up and rigidly connected to and extending between the cen-

tral parts of said side rails, wires connected to and extending between the side rails toward the ends thereof, said wires including helically formed spring portions, upright coil springs mounted on said bars and wires, and locking wires binding the coil springs to the bars and first named wires and means connecting the tops of said upright coil springs.

In witness whereof, I have hereunto set my hand.

REGINALD FERGUSON.
